PREFABRICATED BUILDING CONSTRUCTION

Wallace W. Tiller, Waterloo, Iowa

Application December 22, 1937, Serial No. 181,099

4 Claims. (Cl. 189—1)

My invention relates to improvements in prefabricated building constructions, and an object of my improvements is to provide similar structures therefor, formed and adapted for convenient assemblage and connections, as also for disassembly, storage or transportation.

Another object is to shape and combine different elements in each structure suitable for being associated with others in a completed whole, for either temporary or permanent use, and insulated by non-conducting means therein against variations of temperature of the atmosphere and against permeation of the completed building by extraneous moisture.

Another object of my improvements is to combine with the respective wall and roof elements of the building intermediate connections and supports adapted to render the building resistant solidly against deformation by wind or other pressures exerted against it.

Another novel feature of my improved combination building is the coaction of connected elements in a manner to place all under equalized strain tending to render the structures and building as a whole rigid and secure against vibrations due to any cause of a mechanical nature, or shocks such as explosions, earthquakes or other forces acting thereagainst, either from within or without the building.

Another object of my improvements is to simplify the construction of the elements assembled in each structure, as to render like elements interchangeable accurately with others in a building, and having a simplicity of shapes and coactions such as will render the same inexpensive and requiring a minimum of labor in their assemblage or disassembly.

All of these objects I have attained practically, and by the means which are in the drawings fully illustrated, described and claimed, it being understood that various features of the invention may be modified in materials, construction or shapes, yet not depart from the spirit of the invention.

In said drawings, Figs. 1, 3 and 5 are fragmentary elevations of the wall of my building structures, Fig. 2 is a plan view thereof, Fig. 6 is a vertical sectional view thereof, Fig. 8 is a horizontal section of a detail, and Fig. 7 is a vertical section of a filler device or unit.

In said Figures 1 to 6 inclusive, the construction of each structure is demonstrated in detail. In Fig. 1 the numeral 1 denotes a base block and spaced thereabove is a head block 1. Relatively reversed top and bottom angle-bars 5 and 2 are seated in opposition and vertically spaced apart

in longitudinally hollowed seats in said blocks, and vertical T-bars 3 are rigidly connected thereto by means of bolts 6 and 4 respectively. The base-block 1 and angle-bar 2 are connected by bolts 22 traversing the block. On the inwardly projecting portion of the block 1 are supported parts of a floor board 12 and the mop-board 11. The block 1 has as one inner wall an outwardly inclined part at 21 to seat a removable closure member 29, which is held in place by a long screw 10 or screws 28, the inner end of each being tapped into one of the T-bars 3. 8 is a roof part having a key 9 fitting into a groove along the block 1, secured by nails 10.

A fragmentary filler device 13 shown in Fig. 7 is of rectangular shape and has horizontally spaced walls 14, end closures 13a and spaced pairs of contacting members 19 thereacross dividing the interior into horizontal cells filled with insulation 18.

Against the outer wall 14 of each filler is mounted a sheet of insulation 15, and this in turn is covered by a face-plate 16, parts of pairs of which are slightly spaced apart as shown in Fig. 3, with their approximated vertical edges upset 25 obliquely outward at 16a, as shown in Figs. 3, 4 and 8. Referring now to Fig. 8, which is a fragmentary longitudinal section of the adjacent filler devices 13 and the insulation in the cells thereof, the dividing members numbered 32 are 30 spaced apart with the medial flange 3a of the T-bar 3 seated therebetween, while the outer portions of the spaced members 32 are both recessed oppositely at 32a to produce a cylindric hollow seat to receive a connector body 25 whose outer 35 portion projects beyond the filler device wall 14 and its covering devices 15 and 16 and is terminally coned. A securing pin 31 traverses the body 25 and the T-bar flange 3a, the inner end part of the body 25 being transversely recessed to seat 40 therein an outer part of said flange 3a. The outer part of the body 25 is tapped with an interior thread to receive the threaded end of a headed screw 23.

The outer terminations of the members 32 are 45 beveled outwardly reversely respectively, the insulation 15 covering and conforming to them, as also the obliquely outwardly offset edge portions 16a of the outer plates 16, which are preferably of metal. A vertically disposed angle-bar 17 is 50 positioned to cover the said inclined parts 16 and 15, with a layer of insulation 30 between the angle-bar and the edge parts 16a, and compressed by pressure of the screw 23, a spacer 24 being preferably mounted on the screw 23 be- 55

tween its head and the angle-bar, the spacer being shaped to fit comfortably upon the latter. One or more of these connecting devices are used according to the lengths of the structures. Fig. 5 2 shows the relative arrangement of the above elements on a smaller scale.

It will be noted that as shown in Fig. 8, the screw pressure on the angle-bar 17 compresses the insulation 30 to make a tight joint proof 10 against entrance of air draft or water, but the equalized pressure upon the angle-bar causes the latter to in a measure draw together the oblique flanges 16a, so that in the completed wall structure of the building the wall is rendered tautly 15 assembled to keep its shape and resist strains from within or without, as also longitudinally.

As before stated, the head block 7 with its removable wedge block 28, may have the latter disassembled, when it is desired to place or remove 20 a wall structure. The lower end closure of the filler device 18 shown at 20, is beveled and stepped to conform to another member 21 therebelow. When the upper wedge 28 is secured in place by the long screw 28, the structures are 25 locked in place and cannot be removed outwardly. When the screw 28 is removed, the added clearance space at 27 in the head block 7 with its outwardly inclined wall surface, permits the structure to be swung outwardly at its 30 lower end while disconnecting the engaged blocks 20 and 21, and then lowered for complete separation from the wall. The structure may be replaced by a reversal of the above actions, and held securely tightly in the wall.

35 The above type of demountable structures is particularly suitable in the construction of tabernacles or other temporary buildings which may be moved from place to place compactly, or for storage until needed for rebuilding.

40 I claim:

1. A building component, including a rigid support, an insulated wall member positioned thereagainst, a base member on which the support is removably secured, a head member having a 45 downwardly directed hollow seat to removably inclose the upper part of the wall member, the seat being outwardly widened, a key-block removably fitted in the widened part of said seat, means for separably locking the key-block in 50 the head member when said wall member is seated therein, and a slidably separable seat for the lower end of the wall member permitting, when

said key-block is removed, the downward and outward shifting of the wall member to disengage it from the head member and said support.

2. A building component, including a rigid supporting structure, insulating wall elements 5 removably mounted thereon, outer wall plates in alignment with each other and narrowly separated, the adjacent edge parts of the plates being upset obliquely outwardly, said wall elements having spaced outwardly obliquely directed marginal ribs opposite each other, an angle-bar mounted removably upon and over said wall plate obliquities and oblique ribs, insulating means between said obliquities and ribs, and means for clamping under strain said angle-bar to said wall 15 element and wall plates releasably.

3. A building component, comprising in combination, a rigid skeletal structure, a cellular insulating wall device removably mounted in said structure, a longitudinal head block having upper and lower longitudinal channels therealong, a roof member seated and secured removably in the upper channel, a wedge, the lower channel seating therein together both the adjacent part 20 of the skeletal structure and said wedge, and 25 means for removably securing them therein.

4. In a building component, in combination, closed hollow wall boxings narrowly spaced in alignment horizontally with their opposed end walls stepped apart medially with their wider 30 spacing outwardly, a T-bar having its medial rib seated in their narrower inner spacing to project into their wider spacing and transversely apertured therein, a head block fitted within the wider spacing loosely to project outwardly beyond the casings, a pin traversing said block and rib aperture, the block having an interiorly threaded socket in its outer end alined with said rib, elastic impervious covers for the outer walls 35 of said boxings, metallic covers mounted upon the elastic covers, with the opposed edges of the covers upset outwardly and spaced apart at a desired angle, an angle-bar fitting said opposed parts and apertured in alignment with said socket, a headed and threaded screw seated in said 40 socket and for compressing the angle-bar upon said upset edges, and an apertured spacing member seated upon and across the angle-bar and between it and the head of said screw, whereby the joint between the boxings is imperviously 45 sealed under transverse tension adjustably.

WALLACE W. TILLER.
